United States Patent Office

Des. 198,650
Patented July 14, 1964

198,650

PHOTOGRAPHIC PRINT HOLDER

Robert E. Lewis, Lockport Township, St. Joseph County, Mich. (Rte. 1, Centreville, Mich.), and Philip A. Tunison, Leonidas Township, St. Joseph County, Mich. (824 Olney Road, Leonidas, Mich.)

Filed May 1, 1963, Ser. No. 74,698

Term of patent 7 years

(Cl. D61—1)

We claim:

The ornamental design for a photographic print holder, as shown.
